Patented June 30, 1964

198,523

SELF SERVICE CAR WASH CENTER

Debruedell M. Branham, 2323 Hartford St. SE., 201,
Washington 20, D.C., assignor of ten percent to Marie
Richardson, Washington, D.C.

Filed Aug. 22, 1963, Ser. No. 76,320

Term of patent 14 years

I claim:

The ornamental design for a self service car wash center, as shown.
